UNITED STATES PATENT OFFICE.

FREDERICK H. TIMKE, OF NEW YORK, N. Y., ASSIGNOR TO JOHN KRODER AND HENRY REUBEL CO., OF NEW YORK, N. Y.

DESIGN FOR RUBBER MAT-BINDING.

45,130.

Specification for Design.

Patented Jan. 6, 1914.

Application filed November 1, 1913. Serial No. 798,779. Term of patent 7 years.

To all whom it may concern:

Be it known that I, FREDERICK H. TIMKE, a citizen of the United States, residing in the city of New York, borough of the Bronx, in the county and State of New York, have invented a new, original, and ornamental Design for Rubber Mat-Bindings, of which the following is a specification, reference being had to the accompanying drawing, forming part thereof.

The figure is a perspective view of a rubber mat binding, showing my new design.

I claim:

The ornamental design for a rubber mat binding, as shown.

FREDERICK H. TIMKE.
